MANUFACTURE OF ARTIFICIAL SAUSAGE SKINS

Julius Wolff, Amstenrade, Netherlands; vested in the Alien Property Custodian

Application December 2, 1941, Serial No. 421,397
In Germany May 3, 1937

13 Claims. (Cl. 91—32)

The present invention relates to the manufacture of artificial sausage skins made of tubular fabrics impregnated with suitable materials.

In known devices for the manufacture of artificial sausage skins of the kind mentioned above the tubular fabric is withdrawn from the impregnation mass and drawn upwardly through the annular gap of a stripping off device. The tubular fabric is withdrawn from a mandrel which is arranged vertically in the tank containing the impregnation material. A plurality of impregnating devices with individual tubular fabrics are mounted in a row side by side so that a corresponding number of tubular fabrics may simultaneously be drawn upwardly.

These known devices have the disadvantage that the tubular fabrics together with their supporting mandrels are arranged within the impregnation mass itself. Thus it is not possible or in any case it is very difficult to place large lengths of tubular fabric upon the supporting mandrels, because this would require correspondingly high tanks containing unnecessary large amounts of impregnation material. Moreover, it is undesirable to leave a large stock of tubular fabric, placed upon the supporting mandrels, in the impregnation mass longer than necessary which particularly would be very troublesome upon interruptions of service or at stops or intervals.

In accordance with the present invention these drawbacks are obviated by the fact that the tubular fabrics to be impregnated are arranged upon long mandrels below the tank containing the impregnation material, where they are out of contact with the latter and, therefore, remain dry until the impregnation starts. To this end, circular openings are provided in the bottom of this tank in a number corresponding to the mandrels arranged below said tank. Mounted in these openings are cylindrical bushings provided at the upper end with a flange and through these bushings the tubular fabrics are drawn upwardly. Within each tubular fabric a member is provided at the point of passage through the bushing which together with said bushing forms the annular gap of a size just allowing the tubular fabric to pass through. Mounted upon the upper flange of the individual bushings is the stripping off device for the superfluous material.

The invention has the advantage that tubular fabrics of considerably greater length may be arranged upon correspondingly longer supporting mandrels which, moreover, may be provided below the impregnating tank in a much larger number than hitherto. Furthermore, it is of advan-

tage that within the impregnating tank only the stripping off devices are present and not the supporting mandrels with the tubular fabrics, whereby the entire operation is simplified and rendered easier to be supervised.

In the accompanying drawing a device according to the invention is shown by way of example. In this drawing:

Fig. 1 represents a general view of the device in front elevation showing a longitudinal section through the impregnating tank,

Fig. 2 is a side elevation showing a cross section through the impregnating tank,

Fig. 3 is a broken away vertical section on a larger scale of a detail,

Fig. 4 is a plan view of the impregnating tank and

Fig. 5 is a fragmentary cross-section taken on the line 5—5 of Fig. 3.

The device consists of a frame 1 the upper end of which carries a horizontal trough 2 for the reception of the impregnation material. At the lower end of the frame a pan trough 3 is provided to receive impregnation material which eventually may flow or drip off from the upper trough 2. In the bottom 4 of the upper trough 2 a considerable number of circular holes 5 is provided which serve the purpose of receiving cylindrical guide bushings 6. An enlarged supporting flange 7 is provided at the upper end of each of the bushings which by means of bolts 8 carry a ring 9 spaced a slight distance above the level of the impregnation material. On the central axis of each hole 5 a stationary mandrel 10 stands upon the bottom of the device and this mandrel is tapered from about the height of the lower edge of the bushing 6 to the upper end. This tapered portion 11 extends below the ring 9.

Upon the individual mandrels 10 tube-like supporting sleeves 12 are pushed from above, the lower end of each of which is provided with a flange 13. Tightly slipped over these sleeves is the tubular fabric 14 to be impregnated so that a length of about 100 meters of tubular fabric may be arranged upon each sleeve 12.

The tapered end 11 of the mandrel 10 carries members 15, 16 and 17 having a convex surface by means of which the tubular fabric 14 is slightly tensioned and stretched from within. Above the uppermost member 17 an external wiper ring 18 is easily slidable on the bolts 8. The ring 18 is well rounded off at its inner edge. The ring has a smaller inner diameter than the finished tubular fabric so that the latter in contact with this ring is slightly contracted. At diametrically opposite points the ring 18 is provided with forked

projections 19 which are movably guided along the vertical rods 16.

To impregnate the tubular fabrics 14 the upper end of each of the latter is drawn upwardly through the bushing 6 and the rings 18 and 9 arranged above the latter and are then connected to hooks 21 of a supporting beam 22. If a plurality of rows of tubular fabrics are provided in parallel to each other, a corresponding number of supporting beams 22 is provided which are connected together by holding means 23 adapted to be drawn upwardly by a suitable device to suspend the impregnated artificial sausage skins and to dry same.

As the beams 22, or the holding means 23 are lifted, the length of tubular material is drawn upwardly through the bushing 6. At this point the obturator 15, distends the tube and narrows the gap to an area allowing the passage of the tubular material only and preventing leakage of treating liquid in any substantial amount. The tubular material remains distended until it passes the uppermost distending element 17 when it then is contracted by passage through the wiper ring 18. Thus the excess treating liquid is wiped off of the tubular material. The latter above the ring will dry readily while suspended from the hook 21.

Details described above but not comprehended in the following claims form the subject matter of applicant's copending and companion application for patent on a device for the manufacture of artificial sausage skins filed December 2, 1941, Serial No. 421,398.

What I claim is:

1. Apparatus for impregnating artificial sausage casings and the like comprising a pan, a series of upstanding mandrels mounted in the pan, a sleeve on each mandrel, a trough having apertures through which the mandrels project, and bushings in the apertures around the mandrels cooperating with said mandrels to form annular passageways for the travel of the casings upwardly through the trough.

2. Apparatus for impregnating artificial sausage casings and the like comprising a pan, a series of upstanding mandrels mounted in the pan, a sleeve on each mandrel, a trough supported above the pan and having apertures through which the mandrels project, bushings in the apertures around the mandrels cooperating with said mandrels to form annular passageways and means associated with the trough for drawing the casings upwardly through said annular passageways.

3. Apparatus for impregnating artificial sausage casings and the like comprising a pan, a series of upstanding mandrels mounted in the pan, a sleeve on each mandrel, a trough supported above the pan and having apertures through which the mandrels project, flanged bushings in the apertures around the mandrels cooperating with said mandrels to form annular passageways, means associated with the trough for drawing the casings upwardly through said annular passageways and means carried by said flanged bushings for wiping excess treating liquid from the casings in their upward travel.

4. A device for the manufacture of artificial sausage skins from tubular fabric comprising a stationary member having a convex surface, arranged in the interior of said tubular fabric at the point at which impregnation is effected, said member serving to maintain the portion of said fabric lying in the impregnation material tensioned from within a movably arranged wiper ring, provided above said member having a con-

5. A device for the manufacture of artificial sausage skins from tubular fabric comprising a stationary member having a convex surface, arranged in the interior of said tubular fabric at the point at which impregnation is effected, said member serving to maintain the portion of said fabric lying in the impregnation material tensioned from within, a movably arranged wiper ring.

6. A device for the manufacture of artificial sausage skins from tubular fabric comprising a plurality of stationary members, each having a convex surface, arranged in the interior of said tubular fabric at the point at which impregnation is effected, said member serving to maintain the portion of said fabric lying in the impregnation material tensioned from within, a movably arranged wiper ring provided above said member, having a convex surface and enclosing said tubular fabric and slightly contracting the same, forked projections provided at diametrically opposite points of said wiper ring, and fixed vertical rods along which said lateral forked projections of said wiper ring are loosely guided, so that the latter may be moved freely in vertical and horizontal directions.

7. A device for the manufacture of artificial sausage skins from tubular fabric comprising a plurality of stationary members, each having a convex surface, arranged in the interior of said tubular fabric at the point at which impregnation is effected, said member serving to maintain the portion of said fabric lying in the impregnation material tensioned from within, a movably arranged wiper ring provided above each of said members, having a convex surface, and enclosing said tubular fabric and slightly contracting same, forked projections provided at diametrically opposite points of said wiper ring, and fixed vertical rods along which said lateral forked projections of said wiper ring are loosely guided, so that the latter may freely be moved in a vertical and horizontal direction.

8. A device as set forth in claim 5, comprising a trough containing an impregnation mass, guide bushings mounted in the bottom of said trough, a flange provided on each of said bushings and to which said vertical guide rods for said wiper ring are fixed.

9. Apparatus for impregnating artificial sausage casings and the like comprising a pan, an upstanding mandrel mounted on the pan, a casing sleeve on said mandrel, a trough having an aperture through which the mandrel projects, a bushing in the aperture around the mandrel and cooperating with the latter to form an annular passageway for the travel of the casing upwardly through the trough and means, fixedly mounted on the mandrel within the bushing to restrict said passageway.

10. Apparatus for impregnating artificial sausage casings and the like comprising a pan, an upstanding mandrel mounted in the pan, a casing sleeve on said mandrel, a trough having an aperture through which the mandrel projects, a bushing in the aperture around the mandrel and cooperating with the latter to form an annular passageway for the travel of the casing upwardly through the trough and a bulbous member fixedly mounted on the mandrel within the bushing to restrict said passageway.

11. Apparatus for impregnating artificial sausage casings and the like comprising a pan, an upstanding mandrel mounted in the pan, a casing sleeve on said mandrel, a trough having an aper-

ture through which the mandrel projects, a bushing in the aperture around the mandrel and cooperating with the latter to form an annular passageway for the travel of the casing upwardly through the trough, a bulbous member fixedly mounted on the mandrel within the bushing and a second bulbous member on the mandrel spaced above the first named member.

12. Apparatus for impregnating artificial sausage casings and the like comprising a pan, an upstanding mandrel mounted in the pan, a casing sleeve on said mandrel, a trough having an aperture through which the mandrel projects, a bushing in the aperture around the mandrel and cooperating with the latter to form an annular passageway for the travel of the casing upwardly through the trough, a bulbous member fixedly mounted on the mandrel within the bushing, a second bulbous member on the mandrel

spaced above the first named member and a wiper ring slidably supported above the second named member and having an internal diameter less than that of said second named member.

13. Apparatus for impregnating artificial sausage casings and the like comprising a pan, an upstanding mandrel mounted in the pan, a casing sleeve on said mandrel, a trough having an aperture through which the mandrel projects, a bushing in the aperture around the mandrel and cooperating with the latter to form an annular passageway for the travel of the casing upwardly through the trough, means fixedly mounted on the mandrel for distending the casing, a wiper ring slidably supported above the said means and a stationary ring fixedly supported above the wiper ring.

JULIUS WOLFF.
